ANNULAR TRANSPARENT AQUARIUM

Earl A. Rice, Mercersburg, Pa.

Application December 18, 1950, Serial No. 13,475

Term of patent 14 years

(Cl. D91—2)

To all whom it may concern:

Be it known that I, Earl A. Rice, a citizen of the United States, residing at Mercersburg, in the State of Pennsylvania, have invented a new, original, and ornamental Design for an Annular Transparent Aquarium, of which the following is a specification, reference being had to the accompanying drawing, forming a part thereof.

In the drawing:

Fig. 1 is a front elevational view of the annular transparent aquarium showing my new design.

Fig. 2 is a side elevational view thereof.

Fig. 3 is a rear elevational view thereof.

Fig. 4 is a plan view thereof.

Fig. 5 is a perspective view of the annular transparent aquarium.

Fig. 6 is a sectional view taken on the line 6—6 of Fig. 8.

Fig. 7 is a sectional view taken on the line 7—7 of Fig. 6.

Fig. 8 is a vertical section taken on the line 8—8 of Fig. 6.

I claim:

The ornamental design for an annular transparent aquarium, as shown.

EARL A. RICE.
